(57) **CLAIM**

The ornamental design for a hand tool connection interface as shown and described.

DESCRIPTION

FIG. 1 is a top perspective view of a hand tool connection interface in accordance with an embodiment of the present invention.

FIG. 2 is a bottom perspective view of the hand tool connection interface of FIG. 1.

FIG. 3 is a front view of the hand tool connection interface of FIG. 1.

FIG. 4 is a rear view of the hand tool connection interface of FIG. 1.

FIG. 5 is a right side view of the hand tool connection interface of FIG. 1.

FIG. 6 is a left side view of the hand tool connection interface of FIG. 1.

FIG. 7 is a top view of the hand tool connection interface of FIG. 1; and,

FIG. 8 is a bottom view of the hand tool connection interface of FIG. 1.

FIG. 9 is a cross-section view of the hand tool connection interface of FIG. 1 taken along line 9-9 in FIG. 7.

The portions of the hand tool connection interface shown in broken lines are included for the purpose of illustrating environment and form no part of the claimed design.

1 Claim, 9 Drawing Sheets
